UNITED STATES PATENT OFFICE.

HUGO TUECKMANTEL AND WILLIAM A. LOTZ, OF NEWARK, NEW JERSEY, ASSIGNEES.
TO THE R. NEUMANN HARDWARE CO., A CORPORATION OF NEW JERSEY.

BAG-LOCK.

1,400,640.

Specification of Letters Patent. Patented Dec. 20, 1921.

Application filed August 12, 1921. Serial No. 491,995.

To all whom it may concern:

Be it known that we, HUGO TUECKMANTEL and WILLIAM A. LOTZ, citizens of the United States, residing at Newark, in the county of Essex and State of New Jersey; have invented certain new and useful Improvements in Bag-Locks; and we do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention relates, generally, to improvements in bag-locks; and, the present invention has reference, more particularly, to a novel construction of lock for use in connection with bag-frames of the various kinds, with a view of providing the lock-mechanism thereof with a key-receiving post arranged in a manner and of such construction, so that the hollow or tubular shank of the key can be more easily brought into operative registration with the end of the said post, than is ordinarily the case with the construction of bag-locks, as now generally used.

The present invention, therefore, has for its principal objects to provide a novel and simply constructed bag-lock, in which the key-receiving post is arranged in such a manner, that the end of the hollow or tubular shank of the key can be easily and quickly arranged on the free end of the key-receiving post, for the manipulation of the hasp-engaging lock-mechanism; and, furthermore, to provide in connection with said lock-mechanism and the key-receiving post thereof, a reinforcing element providing a stop for the key when the latter is arranged upon the said post, and also a tubular supporting member mounted upon said post, between the stop portion of the said reinforcing element and the usual spring-actuated key-post and hasp-lug carrier-plate or bridge of the lock.

Other objects of the present invention not at this time more particularly enumerated will be clearly understood from the following detailed description of the present invention. With the various objects of the present invention in view, the said invention consists, primarily, in the novel bag-frame

lock hereinafter set forth; and, the said invention consists, furthermore, in the general arrangement and combinations of the several devices and parts, as well as in the details of the construction of the said parts, all of which will be more fully described in the following specification, and then finally embodied in the clauses of the claims, which are appended to and which form an essential part of the said specification.

The invention is clearly illustrated in the accompanying drawings, in which:

Figure 1 is a top view of fragmentary portions of the usual hinged frame-sections of a bag-frame, one of said frame-sections being provided with a bag-lock made according to and embodying the principles of the present invention, and the other frame-section being provided with a pair of hasps adapted to enter the lock-casing for locking engagement with the mechanism contained in said lock-casing.

Fig. 2, is a longitudinal vertical section of the lock-carrying frame-section, said section being taken on line 2-2 in said Fig. 1, looking in the direction of the arrow x, the lock-casing and the mechanism therein being shown in elevation.

Fig. 3 is a central longitudinal vertical section of both said frame-section and the lock-casing and its mechanism, said view being made on an enlarged scale; and Fig. 4 is a horizontal section of the lock-casing, said section being taken on line 4-4 in said Fig. 3, looking in the direction of the arrow y. Similar characters of reference are employed in all of its said above described views, to indicate corresponding parts.

Referring now to the said figures of the drawings, the reference-character 1 indicates a fragmentary portion of any one of the usual bag-frame sections, provided with an elongated opening as 2, and the reference-character 3 indicates a portion of the other usual bag-frame section, adapted to be closed within the frame-section 1 in the usual and well-known manner. This frame-section 3 is formed with the usual marginal cut away part 4, and is provided with any usual construction of hasps, as 5, substantially as indicated in Fig. 1 of the drawings.

Referring now more particularly to Figs. 2, 3 and 4 of the drawings, it will be seen

that the bag-lock comprises a main shell or casing 6, consisting of a bottom wall 7, end-walls 8, and 9, and a connecting side-wall 10, said casing being usually open, as at 11, 5 opposite the said side-wall 10, as shown in Fig. 4 of the drawings. Suitably secured to said end-walls 8 and 9, by means of rivet-portions or lugs, as 12, is a top-plate 13 made longer than the length of said shell or casing, so that the ends of said top-plate will 10 extend beyond the end-walls 8 and 9, and will provide a pair of fastening lugs or ears 14, which are perforated, as at 15, for the reception of rivets 16, by means of which 15 the said top-plate and the lock-casing or shell 6 are secured upon the inner face of the said frame-section 1, as shown. In its side-wall 10, the said shell or casing is made with a pair of hasp-receiving openings 17 20 into and through which the hasps 5 are adapted to enter for engagement with a pair of hasp-lugs 18, carried by a vertically movable carrier-plate or bar 19. As shown in Fig. 3 of the drawings, the said carrier- 25 plate or bar 19 is provided with suitably disposed holes 20, by means of which said plate or bar is movably disposed upon guide-rods or posts 21, suitably secured at their respective ends to the bottom-wall 7 and 30 the top-plate 13, substantially as shown. Extending upwardly from the central portion of the said carrier-plate or bar 19 is a key-receiving post 22. Also suitably secured to the said carrier-plate or bar 19, by 35 means of fastening lugs 23, or in any other suitable manner, is a bridge which comprises a pair of vertical end-members 24 and a horizontally disposed connecting member 25, the latter having a pair of downwardly 40 extending portions, as 26, connected by a member 27, which is centrally perforated, as at 28, so as to be movably disposed upon the key-receiving post 22, and the said connecting member 25 being perforated, as at 45 29, so as to be movably disposed upon the previously mentioned guide-rods or posts 21. The said connecting member 25 is also provided with a pair of slits 30, or other suitably formed openings, for the reception 50 of a pair of securing lugs 32 which extend from the marginal edge of an elongated housing 31, provided in its top or closed end with a key-receiving hole or opening 33, the said housing extending through an elongated hole 34 in the top-plate 13, and through the hole 2 in the frame-section 1, and in which holes 2 and 34 the said housing is adapted to move up and down. Encircling that portion of the key-receiving 55 post 22, between the carrier-plate or bar 19 and the connecting member 25, is a tubular element 35, in the form of a sleeve or collar, substantially as shown in said Fig. 3 of the drawings. Slightly movably disposed 60 beneath the said carrier-plate or bar 19, upon

said guide-ends or posts 21 is the usual form of snap-plate 36, formed with the usual retaining depressions 37 and 38, and the intermediate projection 39, with either of which is adapted to be brought in slidably clicking engagement a laterally extending latch-stud 41 of the usual key-operated latch-slide 40. The relative and operative positions of the said snap-plate 36 and the carrier-plate 19 are maintained by a bowed spring 42, secured at its center to the lower surface of the said carrier-plate or bar 19, by means of the rivet-head or enlargement 43 of the key-receiving post 22, and the free end-portions of the said spring 42 being in 80 forcible contact with the said snap-plate 36, all of which will be clearly evident from an inspection of said Figs. 2 and 3 of the drawings. 70 75 85 90 95 100

The reference-character 43 indicates the tubular or hollow end of the usual key, which is adapted to be inserted through the key-hole 33 of the housing 31 so as to be readily mounted upon that portion of the key-receiving post 22, which projects above the previously mentioned member 27, in the manner shown in said Fig. 3, for moving the said latch-slide 40 and its latch-stud 41, from its unlocked to its locked relation with the respective parts 37 and 39, or vice versa, from its locked to its unlocked relation, with the respective parts 39 and 37, in a manner, as will be clearly understood from an inspection of said Fig. 3 of the drawings. 105 110 115 120 125 130

The operation of the lock-mechanism will be clearly understood from the foregoing description, and from an inspection of the several figures of the drawings, and any description of the same is therefore deemed unnecessary, except to state that when the key rests upon the upper surface of the connecting member 27, said member serves as a seat for the turning of the key thereon; and should the operator apply too great a downward pressure upon the key, the said tubular sleeve or collar 35 acting as a support or staying element to prevent the connecting member 25 and its parts 26 and 27 from being forced downwardly and out of shape, whereby the mechanism might be rendered inoperative. 110 115 120 125 130

Of course we are aware that some changes may be made in the general arrangement and combinations of the several devices and parts, as well as in the details of the construction of the several parts, without departing from the scope of the present invention as set forth in the foregoing specification, and as defined in the clauses of the claims which are appended to the said specification. Hence, we do not limit our present invention to the exact arrangements and combinations of the various devices and parts as described in the foregoing specification. 130

cation, nor do we confine ourselves to the exact description of the said parts as illustrated in the accompanying drawings.

We claim:

element encircling said key-post between said carrier-plate and the said last-mentioned connecting member of said bridge-element.

7. A bag-frame lock comprising a casing, 5 a locking mechanism therein, a spring-controlled hasp-lug carrier-plate movably disposed within said casing, a key-receiving seat-element disposed above said carrier-plate, and a stiffening element between said 10 key-receiving seat-element and the said carrier-plate.

8. A bag-frame lock comprising a casing, 15 a locking mechanism therein, a spring-controlled hasp-lug carrier-plate movably disposed within said casing, a key-receiving

seat-element disposed above said carrier-plate, said seat-element being provided with a perforation, a key-post extending upwardly from said carrier-plate, and a tubular staying element encircling said key-post 20 between said seat-element and the said carrier-plate.

In testimony that we claim the invention set forth above we have hereunto set our hands this 8th day of August, 1921.

HUGO TUECKMANTEL.

WILLIAM A. LOTZ.
